BRASSIERE

Theo B. Schatimer, Los Angeles, Calif., assignor to Munsingwear, Inc., Minneapolis, Minn., a corporation of Delaware

Filed Dec. 22, 1958, Ser. No. 782,176

2 Claims. (Cl. 128—484)

This invention relates to brassieres, and particularly to brassieres for women having large bust measurements or having pendulous breasts.

Providing an appropriate uplift for a larger woman has been accomplished previously. Wire structures have been provided, for example, along the lower edges of the breast cups. Many women find these constructions irritating and annoying. In other instances, pads have been provided along the lower portion of the breast cups; but this, too, is desirable only for smaller women where the added bulk does not detract from the appearance created.

The primary object of this invention is to provide an improved brassiere structure whereby appropriate uplifting support can be achieved without encountering the foregoing objections. To carry out this invention, use is made of soft, elastic, knitted stretch-yarn bands extending across the lower portions of the cups and of a normal length such that they are flexed and stretched during use so that their resilience provides an appropriate uplifting support.

Another problem in brassieres of this character is that of providing the appearance of a normal separation at the center of the cups. It is not uncommon for women having large bust measurements to prefer cup sizes that will produce a slight bulging at the margin of the cups. It is, accordingly, an object of this invention to provide an improved brassiere structure incorporating means at the center of the garment for maintaining separation or at least the appearance of separation.

This invention possesses many other advantages, and has other objects which may be made more clearly apparent from a consideration of one embodiment of the invention. For this purpose, there is shown a form in the drawings accompanying and forming a part of the present specification. This form will now be described in detail, illustrating the general principles of the invention; but it is to be understood that this detailed description is not to be taken in a limiting sense, since the scope of this invention is best defined by the appended claims.

Referring to the drawings:

Figure 1 is a pictorial view of a brassiere incorporating the present invention, and in place upon the body of the wearer;

Fig. 2 is an inside view of the brassiere structure;

Fig. 3 is an enlarged sectional view taken along the plane indicated by line 3—3 of Fig. 2; and

Fig. 4 is an enlarged sectional view taken along the plane indicated by line 4—4 of Fig. 2.

In Fig. 1 a brassiere structure 10 is illustrated. The brassiere includes a pair of breast cups 11 and 12 connected to a center element 9, a pair of body-encircling bands 13 and 14, and a pair of shoulder straps 15 and 16.

The cups 11 and 12 are each made of three sections of material. The cup 11, for example, includes two lateral sections 17 and 18; section 17 is located adjacent the side of the wearer; and section 18 is located adjacent the center portion of the wearer. These cup sections can be

2

made of any appropriate material, such as broadcloth, cotton, satin or lace. The sections 17 and 18 are joined together by a third section of reinforcing material 19 that extends vertically throughout the height of the cup, and passes over the cup apex. The section 19 furthermore extends beyond the upper edges of the sections 17 and 18. The central section 19, as illustrated in Fig. 4, has lateral edges turned inwardly and sewn respectively to the edges of the sections 17 and 18. Double lines of stitching 20 and 21 are provided for this purpose. Caught under the respective lines of stitching 20 and 21 are inelastic reinforcing straps 22 and 23 of fabric material which serve to transfer forces to the corresponding strap in a manner to be hereinafter described.

15 The edges of cups 11 and 12, where they join member 9, are provided with appropriate gathers, as at 30 and 31, so that an appropriate conical form for the cups is achieved.

At the bottom of the cup 11, a tape binding 24 is 20 provided that is sewn by a double line of stitching 25 to the three sections 17, 18 and 19, as well as to the straps 22 and 23. Binding material 26 is similarly provided along the upper edge of the cup 11.

The upper projecting end of the central section 19, as 25 well as the ends of the straps 22 and 23 are returned to form a loop for purposes of mounting a buckle 27 for the strap 16, said buckle serving as an adjustment means for the strap. The returned portion of the upper end of the central section 19 is fastened beneath the 30 double line of stitching 28.

The inner edges of the central sections 18 of the 35 respective cups 11 and 12 are overlapped and secured together by a double line of stitching 29. The member 9 overlies these abutting edges to form a space for a 35 vertical stay or "bone" 40. The manner in which this stay is held in this space will be described hereinafter.

A unitary band 32 of soft, flexible material, such as 40 elastic knitted stretch yarn, extends along the lower course of both cups 11 and 12 and along the inner side thereof for purposes of achieving appropriate uplifting support 45 for the body of the wearer. The central portion of the band 32 is caught by the spaced line of stitching 29 at the center of the garment. Oblique lines of stitching 33 secure the lower central portions of the band 32 to the respective cups for purposes presently to appear. The band 32 may include alternate narrower bands of relatively tight and relatively loose knitting, the latter being indicated by the shaded strips.

The ends only of the band 32 are connected to the outer 50 edges of the respective cups 11 and 12. One end, for example, is caught beneath the spaced lines of stitching 34 at the side of the cup 11 which provides an appropriate seam for the cup 11. Similar spaced lines of stitching 35 at the outer edge of the opposite cup 12 are also 55 provided.

Also fastened by the lines of stitching 34 and 35 are 60 strips of material 36 and 37 forming pockets to enclose stays 38 and 39, the stays ensuring that the side edges of the cups are maintained appropriately in place adjacent the underarm area of the body of the wearer.

The member 9 (see also Fig. 3) serves to define a 65 pocket for the central stay 40, and its side edges are caught beneath the central parallel spaced lines of stitching 29. This stay or "bone" may be made from a plurality of layers of thin steel or other resilient material.

The stay 40 has an intermediate bulge, as at 40a, which 70 projects outwardly of the garment adjacent the upper area of the stay. The bulge 40a provides a degree of lateral stability so that the stay 40 as a whole is precluded from twisting or moving laterally. It is stabilized by virtue of its bulge nested in the hollow area between the breasts. The bulge 40a maintains the appearance of separation.

even though flesh may enter slightly beneath the stay bulge 40a.

The central parallel line of stitching 29 divides the band 32 into two operative sections, one for each of the cups 11 and 12. The normal free length of each section is substantially less than the length of the lower course of the corresponding cups when in place upon the body of the wearer. For this reason, each of the bands is stretched when the garment is donned. A resilient force is created which provides a comfortable uplifting support at the bottom of each breast. The material readily conforms to the curved contours of the body, and the edges of the band 32 have no tendency to twist or curl. The lower edges of the cups 11 and 12 are freed from strain, and they may easily be maintained against the body without danger of riding upwardly.

The triangular or oblique lines of stitching 33 at the central area of the unitary band 32 prevent a large localized force from being exerted upon the lower ends of the lines of stitching 29, since the lower edge of the band 32 tends to stretch more than the upper edge. Furthermore, the line of stitching 33 transfers the stress imposed upon the band directly to the cups 11 and 12 and a firm support is achieved. When the body moves, the tendency of the band portions to pull the central area of the garment in opposite directions is also substantially minimized, and the central portion of the garment stays adequately in place.

The body-encircling bands 13 and 14 are formed of material similar to the band 32. Both are similarly constructed, and both stretch resiliently when placed upon the body. The width of the band 13, for example, corresponds substantially to half the dimension of the side edge of the cup 11. The band 13 is folded centrally of its length, as at 42, and the ends of the band are located respectively along the upper and lower portions of the side edges of the cup 11. The ends are both caught by the lines of stitching 34. The end edges of the band have a combined length substantially equal to the length of a corresponding side edge of the cup 11 or 12.

To secure the body-encircling bands 13 and 14, tabs 43 and 44 are provided. The band 13 at its folded area mounts one tab 43. The other tab 44 is mounted similarly by the other band 14. The tab 43 mounts two rows of eyes 45, one of which may selectively be engaged by a series of hooks 46 carried by the opposite tab 44.

The upper outer edges of the cups 11 and 12 in brassieres of this general character often tend to fall away from the body of the wearer, but the upper course of each of the bands 13 and 14, by virtue of their place of attachment and their resilience, maintains the side edges of the corresponding cups 11 and 12 adequately in position.

The shoulder straps 15 and 16 are appropriately attached to the garment. Each of the straps 16, for example, is of serially joined, two-part construction. One of the parts is a short section 47 of elastic material. Its lower end is attached to the lower course of the band 13, as by a tack 48, and it is also attached, as by a tack 49, to the upper course of the band 13. The other part 50 of the shoulder strap 16 is of inelastic material, and may be lined with velvet or other soft material. The part 50 is sewn at one end, as at 51, to the upper end of the elastic portion 47, and its other end adjustably cooperates with the buckle 27.

By virtue of the central section 19 of the cup 11 and by virtue of the double lines of stitching 20 and 21, as well as the bindings 22 and 23, the weight imposed upon the cup 11 is effectively transferred to the shoulder strap 16 substantially uniformly throughout the height of the cup 11. A sagging appearance is thus avoided. The body-encircling bands 13 and 14, by virtue of their resilience or elasticity, furthermore readily maintain the lower course of the cups 11 and 12 in place.

The brassiere as a whole provide comfortable support for the woman having larger bust measurements and it makes possible the creation of a pleasant appearance, including the appearance of separation, without requiring uncomfortable wires or extra-heavy padding.

The inventor claims:

1. In a brassiere: a pair of breast cups; means joining the cups together at their inner edges; a stay extending vertically along the joined edges of the cups, said stay having an outward bulge adjacent its upper end providing lateral stability thereof by nesting in the hollow between the breasts of the wearer; stays extending vertically at the lateral or underarm areas of the cups; a band made at least partly of elastic material extending along the lower course of the hollow of each cup and having a normal configuration such that it is longitudinally stretched when the brassiere is donned; each of the bands being secured at its ends only at the inner and lateral edges of the respective cups, whereby there is a free band portion extending substantially entirely across the lower portion of each cup; body-encircling bands for the cups; and a pair of shoulder straps for the brassiere, each strap being secured to a body-encircling band and to a cup.
2. In a brassiere: a pair of breast cups; means joining the cups together at their inner edges; a stay extending vertically along the joined edges of the cups; stays extending vertically at the lateral or underarm areas of the cups; a band made at least partly of elastic material extending along the lower course of each cup and having a normal configuration such that it is longitudinally stretched when the brassiere is donned; each of the bands being secured only at the inner and lateral edges of the respective cups whereby there is a free band portion extending substantially entirely across the lower portion of each cup; body-encircling bands for the cups, said bands each comprising a unitary structure folded in the middle with both ends attached in vertically spaced relationship along the lateral edge of the corresponding cup; cooperable detachable fastener elements secured to the respective body-encircling bands at their folded areas; and a pair of shoulder straps for the brassiere, each strap being secured to a body-encircling band and to a cup.
